UNITED STATES PATENT OFFICE.

FRANCIS M. CASE, OF DENVER, COLORADO.

GLOVE-STRETCHER.

SPECIFICATION forming part of Letters Patent No. 365,432, dated June 29, 1887.

Application filed May 4, 1887. Serial No. 237,055. (No model.)

To all whom it may concern:

Be it known that I, FRANCIS M. CASE, a citizen of the United States, residing at Denver, in the county of Arapahoe and State of Colorado, have invented certain new and useful Improvements in Glove-Stretchers, of which the following is a specification, reference being had therein to the accompanying drawings, in which—

10 Figure 1 represents a plan of my improved stretcher opened, with part broken away, and Fig. 2 the same closed.

This improvement relates to that class of glove-stretchers in which the fingers have a 15 parallel movement in stretching the glove; and the invention consists in the construction, arrangement, and combination of parts, herein-after more particularly described, and then definitely pointed out in the claims.

20 Referring now to the details of the drawings, A A represent two handles pivoted together at B and provided with a spring, C, which is held in position by two teats, D, cast or otherwise formed or attached to the inner 25 side of the handles. These handles are pivoted at E to the hollow finger-sections F F, and to two levers, G G, which are pivoted crosswise to each other at H, and have their free ends slightly curved, so as to work easily be- 30 tween pins I I and the interior surface of the finger-sections, as shown in Fig. 1.

It will be seen from the above description and drawings that when the handles A A are pressed together in opposition to the spring C 35 the levers G G open equally at both ends, and thus the finger-sections open substantially equally at both ends also, which is a great ad-

vantage in glove-stretching, as it stretches all parts of the fingers equally, whereas the glove-stretchers in common use spread more at the 40 tips of the fingers than they do at any other part, which is a great disadvantage.

I am aware that it has been proposed to make stretchers with finger-sections intended to open parallel; but in these the finger-sections 45 opened wider at top than at the bottom, and thus more strain is exerted on the upper portion of the glove material than on that below. Moreover, there is a torsional effect on the rivet connecting the sections, which makes it 50 necessary to have the parts made very strong to resist the strain thereon.

Having thus described my improvement, what I claim as new is—

1. The combination, in a glove-stretcher 55 with suitable handles and finger-sections, of a pair of crossed levers arranged between and operating said finger-sections and connected to and operated by said handles, substantially as described.

2. The combination, in a glove-stretcher, of the pivoted handles A A, the crossed levers G G, connected thereto, and the hollow finger-sections F F, containing said crossed levers and connected to the levers at each end, substan- 65 tially as described.

In testimony whereof I affix my signature, in presence of two witnesses, this 2d day of May, 1887.

FRANCIS M. CASE.

Witnesses:

GEO. A. BOOTH,
E. E. CARTER.

It is hereby certified that Letters Patent No. 365,432, granted June 28, 1887, upon the application of Francis M. Case, of Denver, Colorado, for an improvement in "Glove-Stretchers," was erroneously issued to said Case as owner of the entire interest in said invention; that said Letters Patent should have been issued to *Francis M. Case and Milton E. Heller*, of Defiance, Ohio, said Heller being assignee of one-half interest therein; and that said Letters Patent should be read with this correction therein that the same may conform to the record of the case in the Patent Office.

Signed, countersigned, and sealed this 12th day of July, A. D. 1887.

[SEAL.]

D. L. HAWKINS,
Acting Secretary of the Interior.

Countersigned:

BENTON J. HALL,
Commissioner of Patents.
